UNITED STATES PATENT OFFICE.

DAVID E. HIPOLITO, OF LOS ANGELES, CALIFORNIA; HAZEL C. HIPOLITO, ADMINISTRATRIX OF SAID DAVID E. HIPOLITO, DECEASED, ASSIGNOR TO HERSELF, INDIVIDUALLY.

ADJUSTABLE SCREEN-HANGER.

1,223,281.

Specification of Letters Patent. Patented Apr. 17, 1917.

Application filed June 16, 1910. Serial No. 567,308.

To all whom it may concern:

Be it known that I, DAVID E. HIPOLITO, a citizen of the United States, residing at Los Angeles, in the county of Los Angeles 5 and State of California, have invented a new and useful Adjustable Screen-Hanger, of which the following is a specification.

Objects of this invention are simplicity, cheapness, ease of manufacture, ease of application to the window and ready removal and replacement of the screen.

This invention relates to means for hanging window screens so that they may swing outward at the bottom and may be removed 15 and replaced when desired.

An object of the invention is to make a hanger of the character stated which can be used both for full length and for half length window screens.

20 An object is to provide a screen hinge which can be easily applied from the inside of the building and by means of which the screen can be readily applied to and removed from the window frame by a skilled workman while the workman remains inside the building, thus to make it convenient to apply the screen without the use of ladders, and thus economizing time and avoiding danger.

25 A further object is to make removal of the screen by accident or by an unskilled person more difficult and unlikely than heretofore.

The invention may be applied in various forms.

30 The accompanying drawings illustrate the invention in some of the forms in which it may be embodied.

Figure 1 is a view of a pair of hinges constructed in one form of the invention and 35 assembled as though in use.

Fig. 2 is a fragmentary outside elevation of a window provided with a screen hung by hangers of the form shown in Fig. 1.

Fig. 3 is a sectional elevation from line $\alpha\beta$, 40 Fig. 2, showing the hanger in position with the screen partly open.

Fig. 4 is a face view of one of the swinging members shown in Figs. 1, 2 and 3.

Fig. 5 is a view of a pair of hinges of 45 another form embodying parts of the invention.

Fig. 6 is a view of the parts which go to make up one of the swinging members of the form shown in Fig. 5.

50 In the several views parts that are analogous to each other will be indicated by the same character, an exponent being added to distinguish differences in form of analogous parts.

The frame bracket 1 is a flat plate of sheet metal stamped to provide the main body 2, the upwardly and outwardly projecting supporting lower arm 3 extending in the plane of the plate, and the horizontal retaining arm 4 above the supporting upper arm; there being provided in the bases of said arms, respectively, oppositely arranged notches 5 and 6, one above the other, the notch 5 being in the under edge of the retaining arm 4, and the notch 6 being in the upper edge of the supporting arm 3; and said supporting arm extending above the level of the outlet from said notches and the lower edge of the retaining arm so that removal of the engaging pin or the like of the swinging member of the hinge, by accident or by an unskilled person is unlikely and difficult.

Said plate is provided with two nail holes 7 and 8, one above the other to receive fastening means as screws or nails by which the bracket is secured on the blind stop of the window casing 9. In Fig. 3 nails 10 are shown securing the bracket to the window frame. Preferably the nails employed for this purpose are the well-known cement-coated nails.

The swinging member 12 comprises a main body 13 formed of a plate struck out of sheet metal and provided with a vertical adjusting slot 14 and a screw hole 15 through which screws 16 and 17 are respectively inserted to secure the plate to the screen frame 18. The swinging plate 12 is provided at one edge with a laterally pivotal projection 19, which in some instances is stamped directly from the material forming the swinging plate and in other instances, as shown at 19', is a pivot formed of a piece of wire around which is bent an upper extension 20 of the swinging plate as shown 100 in Fig. 5.

In the form shown in Fig. 1 the pivotal projection 19 is an integral part of the plate which forms the body 13 and said projection also forms the top limb of a loop, the lower limb 21 of which is adapted to contact with the underside of the supporting arm 3; the space between the upper and lower limbs 19 and 21 of the loop is equal to the width of the supporting arm base so that when the 110

screen is hanging vertically the upper and lower limbs of the loops fit against the upper and lower edges of the supporting arms, thus to make a tight joint.

5 The swinging members may also be provided at their edges with fingers 22 bent over to engage the edge of the screen frame. More than one of such fingers may be applied to each swinging member. Preferably 10 one of said fingers 22 is arranged immediately below the loop and another finger 22' may be arranged at the lower end of the plate.

15 The brackets may be provided at their outer edges with gage shoulders 23, 24, which indicate to the eye of the workman the correct position of the brackets on the window frame. The shoulder 24 may be at the end of the open space below the retainer 20 4 and the shoulder 23 may be a straight edge in a line with the shoulder 24 and parallel with the vertical axis of the bracket.

In practice the workman will apply the bracket to the window frame allowing the 25 gage shoulders 23, 24, to be flush with the face of the blind-stop 25 and the top of the bracket to come against the top member 26 of the frame, and will secure them in place by driving the fastening means as the nails 30 10 through the holes prepared therefor.

Then the swinging members will be applied to the screen near the top thereof with fingers, 22, 22' against the edges of the screen stiles, then the adjusting screws 16 35 will be inserted into the adjusting slots 14 so as to hold the swinging plates tightly in position on the screen frame. Then the pivots 19 will be hooked over the supporting arms 3, the lower end of the screen being raised sufficiently to allow the pivots to 40 be inserted between the supporting and retaining arms, and then the screen will be allowed to swing down into closed position, whereupon the workman may adjust the 45 screen by tapping the top of the lower rail or the bottom of the upper rail of the screen to move the screen down or up as occasion may require. When the screen has been brought to the required position so that it 50 swings with satisfactory freedom, then the securing screws 17 will be inserted in place in the holes 15 and all the screws will be tightened, thus securing the swinging members firmly to the screen.

55 In practice when it is desired to swing the screen outward without detaching it, the retaining arms engage the pivotal projection to prevent detachment. By moving the screen away from the brackets so as to swing 60 the pivots or pivotal projections outward

beyond the end of the retaining arm and by lifting the pivots or pivotal projections, the removal of the screen is effected.

The outer and under edge of the supporting arm is preferably curved as shown and 65 the arm broadened downward to its base so that although at the base it fits the space between the upper and lower limbs, it will readily receive the point of the arm.

The operation of mounting the hanger and 70 hanging, removing and rehanging the screen may all be accomplished by a person standing inside the building.

I claim:—

1. In a hinge, a bracket consisting of a 75 flat plate having a main body, an upwardly and outwardly projecting supporting arm having a notch in its base at its upper edge and a retaining arm extending over the plate and having a notch in its under edge above 80 the level of the notched base of the supporting arm, said supporting arm extending above the level of the under edge of the retaining arm substantially as and for the purpose set forth.

2. A window screen hanger comprising a bracket and a swinging member having a laterally projecting pivot to engage the bracket, and also having fingers to engage the edge of the screen stile.

3. A window screen hanger comprising a bracket having an arm; and a swinging member formed of a plate having a laterally projecting loop to encircle and pivotally engage the bracket arm and also having 95 means to engage the edge of the screen stile.

4. In a hinge, a bracket consisting of a flat plate having a main body, an upwardly and outwardly projecting supporting arm extending in the plane of the plate and a 100 horizontally retaining arm above the supporting arm; there being provided in the bases of said arms respectively oppositely-arranged notches one above the other, the upper notch being in the under edge of the 105 retaining arm and the lower notch being in the upper edge of the supporting arm; said supporting arm extending above the level of the outlet from said notches and the lower edge of the retaining arm so that removal from the lower notch, of the engaging element of the swinging member of the 110 hinge is made difficult.

In testimony whereof, I have hereunto set my hand at Los Angeles, California this 115 9th day of June 1910.

DAVID E. HIPOLITO.
